Primary Examiner—Cathron Brooks

(57) **CLAIM**

The ornamental design for a container cap, as shown and described.

DESCRIPTION

FIG. 1 is a perspective view of the container cap showing our new design in its closed orientation;

FIG. 2 is a perspective view of the container cap showing our new design in its open orientation;

FIG. 3 is a top plan view thereof;

FIG. 4 is a front elevational view thereof;

FIG. 5 is a right side elevational view thereof, the left side elevational view being a mirror image thereof;

FIG. 6 is a rear elevational view thereof; and,

FIG. 7 is a top plan view of the container cap showing our new design in its open orientation.
